PULVERIZING APPARATUS

Richard D. Nichols, Columbus, Ohio, assignor to
The Jeffrey Manufacturing Company, a corpora-
tion of Ohio

Application May 22, 1933, Serial No. 672,093

1 Claim. (Cl. 83—11)

The improved pulverizing apparatus represented by the present invention is designed to effect a very substantial increase in efficiency of the forms of apparatus of this general type heretofore employed, through increasing the rate of feed of material to the pulverizing devices utilized in the machine, and imparting to the material an effective preliminary breaking up prior to the complete pulverization of the said material.

5 The present invention relates to a type of grinding or pulverizing apparatus in which the material to be pulverized is fed, in suitably small fragments, to rotary pulverizers operating in opposite directions, to the exterior of which pulverizers the material is fed, and from the interior of which the pulverized material is removed. The removal of the pulverized material is accomplished by a flow of air traversing the pulverizers in opposition to the centrifugal force 10 of the pulverizers acting on the said materials. Machines of this general type include, therefore, a casing forming a single pulverizing zone in which the above-indicated pulverizers are rotated at high speed. The casing has an inner cylindrical wall provided with a hard, abrasive surface or liner, against which the material to be pulverized is impacted by the action of the rotary pulverizing elements. The material to be pulverized is fed to the interior of the cooperating 15 rotatable elements, and the pulverized material is discharged substantially radially therefrom by a blower associated with one of the elements. In the operation of a machine of this design centrifugal force acts in conjunction with the flow of 20 air created by the blower. The efficiency is increased by the removal of the pulverized material which is effected by creating a flow of air through the unit in opposition to centrifugal force acting on the material.

25 40 It has now been discovered that a further substantial increase in the efficiency of the machine may be obtained by providing the rotary pulverizing element positioned adjacent the intake side of the pulverizing chamber, with a plurality of flanges arranged to act with a shearing force on the incoming material and to impact such material against the aforesaid lining of the crushing zone to effect a more thorough preliminary breaking up of the material than has heretofore been the case.

It will be understood that the apparatus is designed to operate on any kind or class of material which it is desired to pulverize, and which is of the requisite degree of softness and friability.

50 55 The air flow through the pulverizing zone is

established by means of a suction fan located at one side of the pulverizing zone, the fan being positioned adjacent the rotary grinding device on the discharge side of the casing, but separated therefrom by an auxiliary wall having an air passage through the center thereof in substantial registry with the air passage through the center of the rotor.

The invention will be more readily understood by reference to the accompanying drawings, in 10 which:

Fig. 1 is a vertical section through a pulverizing apparatus constructed in accordance with the present invention, driving motors for the rotary pulverizers being shown in elevation; 15

Fig. 2 is a sectional view taken generally on the line 2—2 of Fig. 1;

Figs. 3 and 4 are perspective views of opposite faces of the fan side rotor element of the pulverizer shown in section in Fig. 1; 20

Figs. 5 and 6 are perspective views of opposite faces of the intake side rotor element of the pulverizer of Fig. 1; and

Fig. 7 is a side view showing the driving means for the feed mechanism. 25

The pulverizer includes pulverizing apparatus, feeding mechanism therefor, and cooperating fan elements adjacent the intake and outlet passages, the pulverizing apparatus being located intermediate the fans. 30

As shown in Fig. 1, a hopper 1 is provided to receive the material to be pulverized, which, for purposes of illustration, may be specifically coal. A rotary feeder 2 is mounted in the throat 3 above the feeder discharge outlet 4. The throat 3 is 35 attached to a plate 5 mounted on top of the casing 6 in which the pulverizer 7 and the fan 8 are enclosed. The casing 6 is supported on the bed plate or base 9, which also supports the motor 10 for driving the fan shaft 11. The inner end of 40 the shaft 11 carries the fan side rotor element 12 of the pulverizer 7.

The feeder 2 comprises a rotary element 13 mounted on the shaft 14. A plate 15, pivoted at 45 16, rests loosely on top of the rotary element 13. Another plate 17 pivoted at 18 is located below the rotary element 13. The plate 17 is yieldingly supported by the roller 19 pivoted to the inner upper end of the slide rod 20. The rod 20 slides through a wall of the throat 4 and also through 50 a strap 21 secured to the bracket plate 22. A nut 23 screw-threaded onto the rod 20 acts as an adjustable abutment to limit the inward movement of the roller 19. A spring 24 between the nut 23 and stationary strap 21 is compressed when 55

fed below the feed roll 13 and depresses the plate 17.

A permanent magnet 25 attached to a removable cover 26 is placed in the path of the descending material to remove tramp iron from the latter. Such permanent magnet and the feeding apparatus adjacent the same as shown in Fig. 1, may be the same in construction and operation as that disclosed in the patent to Austin A. Holbeck, No. 1,855,171, granted April 19, 1932. If desired, of course, an electromagnet may be substituted for the permanent magnet and arranged to be energized whenever the feeding mechanism 2 is operated.

15 A hollow circular closure 27 for the feed side of casing 6 is provided with a platform 28 on which is mounted the motor 29. The shaft 30 of the latter extends inwardly and carries at its inner end the feed side rotor element 31, which is shown in section in Fig. 1 and in perspective in Figs. 5 and 6. When the motor 29 is operated, the rotor 31 is rotated relatively to the casing 6 and the closure 27 in a direction opposite to the direction of rotation of the fan side rotor element 25 12 which is driven by motor 10. The fan side rotor element 12 is shown in perspective in Figs. 3 and 4.

The feed side rotor element 31 together with the closure 27 and the motor 29 may be moved axially of the shaft 30 and then swung laterally on vertical hinges 32 so that both rotors will be freely accessible for inspection, repair or replacement. The complete supporting structure, and operation thereof, is shown and described in the aforementioned Holbeck Patent No. 1,855,171.

It will be seen from Figs. 1 and 5 that the feed side rotor element 31 is provided with a plurality of radially extending blades 33, illustrated as being three in number, although not necessarily so limited. The rotor 31 is mounted on shaft 30 with the blades 33 adjacent the intake 34 and act as suction fan blades in conjunction with fan 8, to draw material through intake 34 into the pulverizing zone, and to impart to the material a preliminary fracture.

By referring to Fig. 1, it will be seen that the closure 27 when in the position shown provides a feed chamber 35 for the material dropped from the feed mechanism 2.

50 A partition 36 located in the casing 6 is provided with an opening 37 which registers with the openings 38 through the central portion of the fan side rotor element 12. A removable cylindrical liner 39 is provided with circumferentially spaced projections 40 which extend transversely parallel to the axis of the shafts 11 and 30. The inner cylindrical wall of the liner 39 is provided with a multiplicity of transverse grooves to form a serrated inner cylindrical grinding wall 41 closely adjacent to which the radial grinding lugs 42 and 43 on the rotors travel along circumferential paths. Circular shoulders or supporting surfaces are provided on the annular flanges 44 and 45 for engagement by the radial projections 40 to center the liner or hold the same concentric with the axis of the shafts 11 and 30. The circumferentially distributed points of support at 40, 40 lessen the frictional contact to facilitate removal of the liner when desired, but nevertheless the frictional mounting for the liner is sufficient to hold the same in adjusted position against the partition 36 at its rear edge and against the inner edge of the closure 27 at its front edge, and to maintain the 65 opening 46 on its lowermost side in communica-

tion with the tramp pocket 47 in the base 9 as shown in Fig. 1.

When the material, such as coal, to be pulverized falls to the bottom of the chamber 35, it will tend to accumulate therein, at least to a certain extent, but the suction action of the fan blades 33, acting in conjunction with the fan 8 to draw the material into the pulverizing rotors, prevents any material amount of accumulation. Angle member 48, extending across the chamber 35, is 10 designed to catch pieces of tramp iron, preventing the same from contacting with the rotor 31. If, however, pieces of such tramp iron do come into contact with the rotor 31, the larger pieces will be ejected by the rotor and remain in the bottom of the chamber 27. Smaller pieces of tramp material that may pass by the crusher lugs 43 will escape through the openings 49, 49, normally closed by the cover plates 50, 50.

15 Inasmuch as the rotor disc 31 is closed, the material to be pulverized must find its way peripherally of the disc 31 between the grinding lugs 43 into the pulverizing zone. This action is greatly facilitated by the suction created by the fan blades 33 which act in conjunction with the fan 8 to draw the material from chamber 35 into the pulverizing zone and which preliminarily pulverize the material by impacting it against the grinding surface of the liner 39. As the material is thus sucked, peripherally of the disc 31, and between the grinding lugs 43 into the pulverizing zone, it is ground by impact against the leading sides of the lugs 43 and against the serrated cylindrical wall of the liner 39.

30 The sucking action above referred to is produced by cooperation of fan blades 33 and fan 8, the latter producing a current of air from the feed side of the disc 31, which feed side carries the blades 33 into the hollow chamber between the rotor elements 12 and 31. Whatever material passes to the peripheral space surrounding the rotor 12 will be further crushed by impact against the radial spaced-apart lugs 51, and by being thrown by the latter against the 35 serrated cylindrical wall 41.

35 While the suction of the air through the opening 37 tends to draw the crushed material through the peripheral space between the lugs 51 and the serrated wall 41 and radially to the 40 left of the rotor 12 as viewed in Fig. 1, this tendency is counteracted by the radial fins 53, 53 which are formed in radial continuation of spider arms 54, 54 and by the auxiliary radial fins 55, 55, intermediate the fins 53, 53, as shown in Fig. 3. The faces of the fins 53 and 55 adjacent to the inner wall of the partition 36 are approximately in the same vertical plane which is closely adjacent to such inner wall. Consequently, an effective seal will be produced to prevent 55 the passage of coarse material between the back 60 of the rotor 12 and the adjacent wall of the partition 36.

The rotor 31 is provided with parallel spaced-apart pulverizing lugs 56, which may be integral with the grinding lugs 43, but the spacing between the latter is shorter than the spacing between the grinding lugs 43. The rotor 12 is provided with similarly spaced pulverizing lugs 51, which overlap the lugs 56 so as to leave only 70 a small cylindrical space 58 between the paths of travel of the adjacent faces. It is preferred to arrange the parallel lugs 56 and 51 so that the path of travel of the feed side rotor pulverizing lugs 56 will be of smaller diameter than the 75

path of travel of the fan side rotor pulverizing lugs 51. This arrangement enables the grinding lugs 43 to be placed adjacent the serrated wall 41 while providing sufficient space between the lugs 43 for entrance of the material into the pulverizing zone, and, moreover, the entrance to the ring space between the paths of travel of the adjacent faces of the pulverizing lugs 56 and 51 will be nearer the lugs 43 to lessen the tendency of the material to pass between the back of the rotor 12 and the adjacent wall of the partition 36.

It should be particularly understood that the rotors when operating are driven at high speed in opposite directions and therefore the lugs 56 and 51 act as ejectors to prevent coarse particles from passing between the same into the hollow chamber 1, which action is further enhanced by the preliminary pulverization effected by the blades 33. The centrifugal forces acting on the material, moreover, are in opposition to the inward air current produced by the blades 33 and fan 8. The oppositely rotating rotors therefore act to separate automatically the fine particles from the coarse, the coarse particles being continually thrown outwardly against the serrated wall 41 while only the finest or pulverized material flows with the air through the opening 37 into the fan chamber 59.

50 The coarser particles continue to be pulverized by impact and attrition around the circumferences of the rotors until they are so fine that the centrifugal forces of the rotors no longer eject them outwardly. Only the extremely fine material is pulled through the ring space 58 by the air current produced by the fan 8 into the fan chamber 59. Pulverization is completed in the ring space 58 or between the overlapping adjacent faces of the pulverizing lugs 56 and 51 because actual tests show that the maximum wear takes place at such adjacent faces and at the leading corners as illustrated at 60, 60 in Fig. 2, the direction of rotation of the rotor 12 being in the direction of the arrow. The same is true 45 with respect to the wear on the lugs 56 of the feed side rotor 31.

In order to drive the feeding mechanism 2 from the shaft 11, a pulley 61 on the latter is connected by a belt 62 to a pulley 63 which is 50 loosely mounted on the shaft 64 of the speed reducer 65. The shaft 66 of the latter is connected to a disc 67. On the shaft 14 of the feed roll 13 is mounted an arm 68 which is pivotally connected to a link 69. The latter is adjustably 55 connected to a diametrical slot 70 on the disc 67.

A clutch 71, which is adapted to be spring released, is associated with the pulley 63, the outer clutch element 72 being splined on the shaft 64. An electromagnet 73 mounted on the bracket 74 secured to the hopper 1 may be employed to pull the rod 75 to the right as viewed in Fig. 1, thereby swinging the lever 76 on its pivot 77 to apply the clutch 71 and thus connect the shaft 11 to the speed reducer 65. The lower end of lever 76 is pivotally supported on bracket 78 secured to the fan housing 6. A shifter 79 connects the lever 76 to the clutch element 72. Although the shaft 11 rotates at a high speed, the speed reducer 65 will effect relatively very slow 70 operation of the feeding mechanism 2.

On account of the high speed of rotation of the shaft 11 and the parts connected thereto including the armature of the motor 10, there will be considerable momentum tending to continue 75 rotation of the shaft 33 after the current to the

motor 10 has been cut off. It is desirable to stop the feeding mechanism as soon as the current to the motor 10 is shut off, and therefore the electromagnet 73 is arranged to be deenergized so that the clutch 71 will be released and the feed mechanism 2 stopped as soon as the motor current is interrupted.

Where the present apparatus is installed in connection with a heating system, or where the installation is such that the quantity of air mixed 10 with the pulverized material is of importance, in order to assure an ample supply of air, there is preferably provided an air intake opening at 80 regulated by a shutter 81 operable by the handle 82. The mixture of air and pulverized 15 material, such as coal, is forced by the blower fan 8 into any suitable conduit or receiver, not shown.

Reverting to the operation of the pulverizer comprising the oppositely rotating elements 12 20 and 31, it should be noted that the construction is such as to maintain the same entirely open at all times for free and uniform flow of air during pulverization. The coal or other material to be pulverized is fed gradually into the 25 chamber 35, whence it passes into engagement with the blades 33 on the feed side rotor 31. These blades 33, rotating at high speed, project the entering material against the surface 41, where it is initially pulverized. It will be further observed that the blades 33 and the grinding lugs 43 are arranged in staggered relation 30 relatively to each other, so that the material, as it is initially pulverized and fed into the space between the grinding lugs 43 and grinding surface 41, through the action of the blades 33, will be picked up by lugs 43 and further pulverized before passing into the ring space 58. The feed side lugs 43 and 56 keep the material from accumulating at any portion of the wall 41 of the 40 liner 39, so as to permit free passage of the air and coal into the ring space 58 between the lugs 56 and 51. The outer ends of the lugs 43 are closely adjacent the serrated wall 41 and this, together with the initial pulverization produced 45 by the action of the blades 33, substantially advances the pulverizing action before the material reaches the oppositely moving lugs 56 and 51.

The radially projecting lugs 51 closely adjacent the serrated wall 41 act to keep the space 50 surrounding the lugs 56 open for free access of air through these lugs into the chamber 1 between the rotor elements. Air may pass through the spaces between the lugs 57 as well as between the spaces between the lugs 56 into the chamber 55 1, drawing the finely pulverized material therewith, coarse particles being ejected outwardly against the wall 41. When the particles enter the space 58 they are pulverized by impact and attrition effected by the rapidly rotating lugs 56 60 and 51 passing each other in opposite directions.

The radial ribs or fins 53, 55 in addition to strengthening the fan side rotor element 12, also seal the space between the back of the rotor element and the adjacent wall of the partition 36 65 against the passage of any coarse particles through such space to the opening 37. Such ribs or fins set up a fan action counteracting the tendency of the fan 8 to produce a current of air through such space. The air entering the 70 pulverizing zone is therefore prevented from being by-passed into the fan housing without going through the lugs 56 and 51 of the rotors.

Obviously those skilled in the art may make 75 various changes in the details and arrangement

of parts without departing from the spirit and scope of the invention as defined by the claim hereto appended, and I wish therefore not to be restricted to the precise construction herein disclosed.

Having thus described and shown an embodiment of my invention, what I desire to secure by Letters Patent of the United States is:

A pulverizing apparatus comprising the combination with a casing, of two overlapping concentric rotor elements comprising spaced-apart series of pulverizing lugs parallel to the axis of rotation of the said rotor elements, separate motors one of which is connected to each of said 10 rotor elements to rotate the same in opposite directions, means affording an entry opening into the said casing for the material to be pulverized, a plurality of blades on the rotor element adjacent the said entry opening, and adapted to engage material passing into the entry opening and to project the said material against the cas-

ing for effecting preliminary fracture of the said material, peripheral spaced-apart preliminary grinding devices on the said rotor element adjacent to the said entry opening, a cylindrical grinding wall adjacent to the path of the said 5 preliminary grinding devices, the rotor element adjacent the entry opening comprising a closing disk carrying the said blades, the blades producing a fan action impelling the preliminarily fractured material to rotate peripherally of the last-named rotor element to the pulverizing lugs, spaced-apart peripheral grinding devices adjacent the grinding wall and mounted on the rotor element spaced from the entry opening, the last-named rotor element having an exit opening in 10 the central portion thereof, the said grinding devices being positioned intermediate the blades and said exit opening so as to act upon the material as it is projected between the said device 15 and the grinding wall by the said blades.

RICHARD D. NICHOLS.
